JOSEPH W. GAMBLE, OF PHILADELPHIA, PENNSYLVANIA, ASSIGNOR TO HARRISON SAFETY BOILER WORKS, OF PHILADELPHIA, PENNSYLVANIA, A COPARTNERSHIP.

VALVE.

1,172,272.

Specification of Letters Patent. Patented Feb. 22, 1916.

Application filed November 4, 1913. Serial No. 799,081.

To all whom it may concern:

Be it known that I, JOSEPH W. GAMBLE, a citizen of the United States, residing at Philadelphia, in the county of Philadelphia and State of Pennsylvania, have invented 5 certain new and useful Improvements in Valves, of which the following is a specification.

This invention relates to valves and is directed particularly to the provision of a 10 check-valve adapted to operate on low pressures, such for instance, as pressures under one pound. Check-valves of this character are of special utility in connection with installations of turbines of the bleeder type.

The invention involves the provision of a 15 valve having one or more movable valve-members, each of which is provided with a spring arranged to lift the valve-member from its seat, but having insufficient tension to effect such lifting of the valve-member when unaided by pressure upon the valve-member. Such a spring acting upon the 20 movable valve-member serves to sustain a portion of the weight of the valve-member so that the pressure upon the valve-member is required to lift a portion only of the 25 valve-member in order to open a passage for the escape of the steam.

In the preferred embodiment of the invention, a plurality of movable members are employed governing individual openings through which excessive pressure conditions 30 are relieved. Each of these valve-members normally rests by gravity upon the valve-deck in which the openings are formed in order to close those openings and a rise of 35 pressure tends to lift the valve-members from their seats. The springs above mentioned are arranged to assist in this raising movement. Thus if one or two of the valve-members become stuck to their seats there 40 will still be one or more others which will respond to the excessive pressure and operate to relieve it. Also, the provision of 45 springs arranged to sustain a portion of the weight of the movable valve-members makes it possible to have the valve respond to a rise of pressure of a very small amount, such 50 for instance, as a rise to six or eight ounces. Preferably a pressure plate is mounted stationarily within the casing of the valve on which all of the several springs employed 55 bear at their lower ends, the upper ends of these springs being connected to the stems

of the valve-members. Also, each valve-member is preferably provided with a dash-pot to regulate its movements.

The preferred embodiment of the invention is shown in the accompanying drawings, in which—

Figure 1 is a central vertical section of a 60 valve and Fig. 2 is a horizontal section showing the pressure plate and the parts associated therewith in plan view.

Referring to these drawings, 3 indicates 65 the casing of the valve having an inlet opening 4 and an outlet opening 5 formed therein. This valve is arranged to be horizontally disposed in a length of steam piping. Within the casing 3 is a horizontally disposed valve-deck 6 having a plurality of openings therethrough, each of which is adapted to be closed by a movable valve-member 7. The casing 3 of the valve has 70 walls 8 and 9 formed integral therewith with which the valve-deck 6 coacts so that the valve-members 7 control the passage of steam through the valve. The valve-deck 6 is secured in position in coaction with the 75 walls 8 and 9 by a bolt 10 extending through a spacer 11.

A pressure plate 12 is mounted above and 80 parallel to the valve-deck 6. It is secured 85 stationarily in position by a bolt 13 passing through the pressure plate and entering the valve-deck, a spacer 14 being employed for separating the valve-deck and pressure plate the requisite amount. In addition to the 90 bolts 10 and 13 and the spacers coacting therewith, additional bolts and spacers may be employed, as indicated, for holding the valve-deck 6 rigidly upon its seat upon the walls 8 and 9 and for mounting the pressure plate 12 fixedly within the casing parallel to 95 and at a definite distance from the valve-deck 6.

Each of the movable valve-members 7 is provided with a stem 15 extending upwardly 100 from the valve-member through an opening in the pressure plate 12. A spring 16 is coiled about each valve-stem 15 above the pressure plate 12 and has its lower end lying within a cup formed in the upper face of the pressure plate and resting upon the pressure plate. The upper end of each spring 105 16 is received within a cap 17 secured upon the valve-stem 15. Each movable valve-member 7 is also provided with a dash-pot. On the under side of the valve-member is a 110

cylindrical extension 18 constituting a piston which is received within a cylinder 19 sustained by a holder 20 formed in the casting for the deck-plate 6.

5 Each of the springs 16 is compressed slightly between the deck-plate 12 and the cap 17 which is secured to the stem 15. Because of this compression, the spring 16 tends to lift the corresponding valve-member 7 from its seat upon the deck-plate. Since the valve is disposed horizontally, the valve-member 7 tends to move by gravity downwardly upon its seat. The degree of compression of the spring 16 between plate 12 and cap 17 is such that the spring alone will not effect lifting of the valve-member 7. The spring is capable of sustaining but a portion of the weight of the movable valve-member 7. Therefore the valve-member 10 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 It is hereby certified that in Letters Patent No. 1,172,272, granted February 22, 1916, upon the application of Joseph W. Gamble, of Philadelphia, Pennsylvania, for an improvement in "Valves," an error appears in the printed specification requiring correction as follows: Page 3, lines 79-80, claim 3, for the word "casting" read *casing*; and that the said Letters Patent should be read with this correction therein that the same may conform to the record of the case in the Patent Office.

Signed and sealed this 14th day of March, A. D., 1916.

[SEAL.]

J. T. NEWTON,

Acting Commissioner of Patents.

Cl. 137—32.
